UNITED STATES PATENT OFFICE.

EDWIN BENNETT, OF LONDON, ENGLAND.

APPARATUS FOR ROASTING COFFEE.

SPECIFICATION forming part of Letters Patent No. 698,246, dated April 22, 1902.

Application filed July 22, 1901. Serial No. 69,216. (No model.)

To all whom it may concern:

Be it known that I, EDWIN BENNETT, a subject of the King of England, residing at London, England, have invented certain new and useful Improvements in or Relating to Apparatus for Roasting, Drying, and Similar Purposes, (for which application has been made in Great Britain under No. 9,271, dated May 4, 1901,) of which the following is a specification.

This invention relates to apparatus for roasting, drying, and similar purposes, and refers more particularly to apparatus for roasting coffee. With apparatus of this class as hitherto constructed the heat for performing the roasting has been applied externally from a gas or other furnace or burner, so that before reaching the material under treatment it has to heat up and penetrate the outer casing of the apparatus, whereby a considerable amount of heat is wasted.

It is the chief object of my invention to provide an apparatus in which the heat is applied to the material to be roasted from the interior.

According to my invention I employ a revolving, oscillating, or other drum or cylinder provided with an inner perforated casing disposed between the material to be roasted and a heated bolt or core or a chamber heated by any appropriate means. The drum or cylinder may be rotated by hand or other power and is preferably provided with a sliding or other door, through which the material may be inserted into or withdrawn from the interior of the drum. This door may conveniently be formed of wire-gauze or perforated metal, so as to enable the progress of the roasting to be readily watched. When a bolt is used for supplying the necessary heat, I provide at one end of the revolving drum a hollow journal, through which the heated bolt can be inserted into the interior of the aforesaid perforated casing, said bolt being supported at the other end of the drum by an inwardly-extending projection. The bolt may be heated in a separate furnace and is preferably provided with a handle or other device by which it can readily be inserted into or withdrawn from the interior of the casing, or I may employ more than one bolt arranged at suitable intervals around the interior of the perforated casing.

The inner cylinder may consist of a sheet of wire gauze or netting or a sheet of perforated metal, according to the nature of the material under treatment. Around the interior of the drum or on the exterior of the inner casing I may provide one or more radial projections or arms which act as baffles for stirring up the material or for holding part of it stationary for inspection purposes.

Instead of employing a bolt or core heated in a separate furnace previously to its being inserted into the casing I may employ a bolt heated by electricity, or I may employ other electrical heating means. I may also employ one or more chambers or compartments disposed within the casing and heat them directly by gas or other appropriate means.

Referring to the drawings, Figure 1 is a side elevation. Fig. 2 is a transverse section on the line 2 2 of Fig. 1, and Fig. 3 is a longitudinal section through an apparatus constructed in accordance with my invention.

A is the drum or cylinder, B the inner perforated casing or screen, and C the heating bolt or core.

The drum A is mounted on a stand or support D, which is provided with bearings D', one of which is adapted to receive a shaft or spindle A', projecting from the end of the drum, and the other of which receives a hollow journal A², formed in one with or connected to the other end of the drum. The heating-bolt C is inserted into the interior of the drum through the hollow journal A². On its outer end the bolt is provided with a flange or collar C', which fits tightly into the hollow journal and is formed with a hole in its inner end, into which a projection A³ on the end of the drum enters to form a support for the bolt.

The perforated casing or screen B is formed of a piece of wire gauze or netting and encircles the heating-bolt, being secured to flanges or collars A⁴ at each end of the drum.

The material to be roasted or dried is inserted into the drum through the door E, which slides in guides A⁵. The door is provided with transverse slots E', through which the contents of the drum may be inspected.

Adjacent to the door E is a radial projection or arm B', connected to the inner casing B, or it may be connected to the inner side of the wall of the drum. As the drum is rotated this arm stirs up the material within the drum

and carries some of it around with it, so that the progress of the heating or roasting may be noted by examining the portion of the material held stationary by the arm.

5 5 The bolt is preferably provided with a rod C³, on the outer end of which is mounted a wooden or other handle C⁴, by means of which the bolt may readily be withdrawn from the drum to be heated in a separate furnace and thereafter be again inserted into the drum.

10 The drum is rotated by hand by means of a crank and handle F, mounted on the end of the spindle A', or I may provide the rod C³ with a device operated by hand or other power 15 for rotating the apparatus, or the drum may be rotated by any other convenient means.

15 Instead of imparting a rotary movement to the drum it may be given an oscillatory or other suitable motion.

20 20 What I claim as my invention, and desire to secure by Letters Patent, is—

25 1. In an apparatus for roasting, drying and similar purposes the combination with a rotatable chamber of a heated bolt removably arranged within the chamber and a perforated 30 casing encircling the bolt as and for the purpose specified.

30 2. In an apparatus for roasting, drying and similar purposes the combination with a chamber of a removable heating-bolt disposed within the chamber, a perforated casing placed between the bolt and the material under treatment, a door in the chamber and means for rotating the apparatus.

35 3. In an apparatus for roasting, drying and

similar purposes, the combination with a chamber of a heated bolt disposed within the chamber, a perforated casing between the bolt and the material under treatment, a door in the chamber, a hollow extension on one 40 end of the chamber for the reception of the bolt and an inwardly-extending projection on the other end of the chamber to support the bolt substantially as described.

4. In an apparatus for roasting, drying and 45 similar purposes the combination with a chamber of a heated bolt disposed within the chamber, a perforated casing between the bolt and the material under treatment, a door in the chamber, a hollow journal on one end of the 50 chamber for the reception of the bolt, an inwardly-extending projection on the other end of the chamber to support the bolt and a radial arm within the chamber substantially as and for the purpose described. 55

5. In an apparatus for roasting, drying and similar purposes the combination with a chamber of a heated bolt disposed therein, a perforated casing placed between the bolt and the material under treatment, a radial arm 60 on the inner casing, a door in the outer casing and means for rotating the chamber.

In testimony whereof I have signed my name to this specification in the presence of two subscribing witnesses.

EDWIN BENNETT.
